RADIO PROGRAM SELECTOR

Paul R. Prescott, Logansport, Ind.

Application September 20, 1938, Serial No. 230,869

3 Claims. (Cl. 250—20)

This invention relates to radio program selectors and has for an object to provide simplified apparatus whereby one may select a list of radio programs in which he is interested and set the instrument according to the times during which the programs are to be given so that the desired stations are automatically tuned in during the entire 24 hour day without requiring further attention.

10 The distinctive structure for carrying out the above general object of the invention includes a clock adapted to strike quarter hours, a contact carried by the striking arm of the clock and adapted to actuate a motor starting relay, means connected to the motor shaft for stopping the motor, a switchboard having thereon a plurality of manually operable dial switches representing quarter hour periods, and means connected to the motor shaft for completing a circuit through 15 any one of the closed dial switches to control a tuning relay and a power relay for tuning in and out selected programs.

With the above and other objects in view the invention consists of certain novel details of 20 construction and combinations of parts herein-after fully described and claimed, it being understood that various modifications may be resorted to within the scope of the appended claims without departing from the spirit or sacrificing 25 any of the advantages of the invention.

In the accompanying drawings forming part of this specification,

Figure 1 is a fragmentary front elevation of a switch board having mounted thereon manually 30 operated dial switches, one for each quarter hour through the 24 hours, adapted to be selectively set to tune in a selected broadcasting station at a predetermined time.

Figure 2 is a fragmentary vertical sectional view taken on the line 2—2 of Figure 1, and reading from left to right, showing the hour selector switch, resetting switches for the power relay and for the tuning circuit relay, motor relay reset switch, quarter hour selector switches, 45 and brush contacts for the quarter hour selector switches electrically connected to the hour selector switch.

Figure 3 is a cross sectional view taken on the line 3—3 of Figure 2 showing the reverse side 50 of the hour selector switch, contact arm, and ratchet device for advancing the arm one step each hour.

Figure 4 is a cross sectional view taken on the line 4—4 of Figure 2 showing the motor, worm 55 pinion, worm gear, and motor relay reset switch.

Figure 5 is a cross sectional view taken on the line 5—5 of Figure 2, showing one of the quarter hour selector switches.

Figure 6 is a diagrammatic view showing the electrical connectors of the various devices of 5 the radio program selector.

Figure 7 is a longitudinal sectional view of the switch for closing the power relay and tuning relay resetting circuits.

The switchboard

10

Referring now to the drawings in which like characters of reference designate similar parts in the various views, 10 designates a switchboard, shown best in Figure 1, and mounted thereon are 15 program selector switches 11 of the dial type arranged in rows vertically and horizontally, there being 24 vertical rows of switches representing hour periods, there being four horizontal rows representing consecutive quarter hour periods of 20 each hour, making 96 switches in all. These switches, in the present embodiment each have four contacts 12, best shown in Figure 6, corresponding to different broadcasting stations, although as many stations as desired may be represented by contacts, and an off contact 13, the movable switch arm 14 of the switch being placed in engagement with the contact representing any desired station or being turned to the off position when no station is wanted at that particular time period represented by any dial switch. The device may be constructed to control tuning 25 for less than 24 hours.

The motor and control relay therefor

35

By now referring to Figures 4 and 6 it will be seen that an electric motor 15 is secured to the base 16 of the cabinet upon which the switchboard is mounted. The motor is energized each quarter hour of the day and night through the 40 medium of a conventional clock 6 adapted to strike the quarter hours and having a contact 17 on the striker 18 which engages and closes a circuit closer 19 connected by conductor wires 20 and 21 to the low voltage secondary winding of 45 a transformer 22 the primary winding of which is connected to the 110 volt service line 23. When the circuit closer 19 is operated, a relay 24 connected in the low voltage circuit 20—21, is energized and the contact points 25 of the relay are 50 engaged to close the motor circuit comprising the wires 26 and 27, see Figure 6, to the service line.

The motor rotates a main shaft 28, see Figures 2 and 4, through a quarter turn on the quarter 55

hour, that is, one full revolution each hour. The shaft is driven by the motor through the medium of a worm gear 29 keyed to the shaft and a pinion 30 carried by the motor shaft, as shown in Figure 4.

To halt the shaft at the end of each quarter revolution the gear 29 is provided with four pins 31 spaced at 90 degrees apart on the side of the gear. A motor relay reset switch 32 is mounted 10 on a bracket arm 33 which rises from the base 16. Assuming the rotation of the gear to be in the direction of the arrowhead shown in Figure 4, at the end of a quarter turn, the pin in rear of the arrowhead will have advanced into contact 15 with the movable arm of the switch and will move the switch to circuit closing position.

The switch 32 controls a circuit comprising wires 34 and 35, see Figure 6, having an electromagnet 36 connected therein which when energized, attracts the armature of the relay 24 to open the motor circuit at the contacts 25 and stop the motor and consequently halt the shaft 28 which in the meantime has operated various electrical devices to tune in the desired station as 25 will now be described.

The quarter hour selector switch

By referring to Figure 2 it will be seen that the shaft 28 is journaled in a bearing bracket 37 and 30 is fixed in one end of a sleeve 38 which rotates as a unit with the gear and has a stub shaft 39 fixed in the other end and journaled in a bearing bracket 40. The sleeve shaft 28 simultaneously 35 actuates a plurality of quarter hour selector switches 42, of the ignition timer type, one of which is shown in Figure 5. There is one of these switches for each hour period, making 24 in all, corresponding to the 24 hours of the day. Each switch has an annular casing provided with four 40 equally spaced switch contacts 43 corresponding to quarter hour time periods. The casing is secured to spaced bars 44 carried by the bearing bracket 40 and a post 45 which rises from the base 16, as shown in Figure 1. The spring pressed 45 circuit closing arm 46 of each switch is pivotally mounted on a metal sleeve 47 which is fixed to the sleeve shaft 38 which latter is formed of insulating material and houses the wires 50 which supply current to all of the quarter hour selector switches. As best shown in Figure 6 the four 50 equally spaced contacts 43 of each $\frac{1}{4}$ hour selector switch 42 are connected to the movable switch arms 14 of the four dial switches 11 of a corresponding hour time period. The four stationary contacts of each of said dial switches are connected by wires 51 and 52 to respective tuning 55 relays 53, which will be presently described.

Brush contacts and hour selector switch

60 A plurality of brush contacts, 24 in all, are provided each comprising a commutator ring 54 which is mounted upon an insulating cylinder 54' which is fixed to the sleeve shaft 38. Each ring is connected to one of the current supply wires 50 65 of a respective quarter hour selector switch. Brushes 55, carried by one of the bars 44, have wiping engagement with the rings. The brushes are connected to respective current supply wires 56 which are conducted through an insulating 70 sheath 57 to the hour selector switch 58 best shown in Figures 2 and 3.

The hour selector switch comprises a disc of insulating material which is fixed stationary to a bracket arm 59 which projects laterally from a 75 standard 60 secured to the base 16 near the

switchboard 10. An annular series of switch contacts 61 project through the disc, concentric with the axis of the disc, there being 24 of these contacts corresponding to the 24 hours of a day. The conductor wires 57 of respective brushes 55 5 are connected to respective ones of these contacts 61.

A step rotated shaft 62 is engaged loosely through the center of the disc 58 and is journaled at one end in a bearing 63 mounted on the post 10 60. The other end of the shaft projects through the switchboard and is equipped with a knob 64 to permit the shaft to be manually turned to synchronize the program selector switch with local time. A circuit closing arm 65 is fixed to 15 the shaft and is provided with a spring pressed plunger 66 which has wiping engagement with the contacts 61 when the arm is rotated, one step each hour, to circuit closing position with the contacts 61 successively. A helical spring 67 is 20 sleeved on the shaft 62 between the base of the circuit closing arm 65 and the bearing 63 to frictionally engage both of the latter parts and halt rotation of the shaft sharply after each 25 step rotation.

Current is supplied to the circuit closing arm 65 through the medium of a conductor wire 68 which is connected to the bearing 63 and to the secondary winding of the step down transformer 22, as best shown in Figure 6. When the circuit 30 closing arm is in circuit closing position with one of the contacts 61, current is supplied to a respective quarter hour selector switch 42, and from the latter to the four respective dial switches 11 and then, should one of the said four dial switches 35 be closed, to the respective tuning relay 53 as will presently appear.

Ratchet drive for hour selector switch

The shaft 62 of the hour selector switch is 40 equipped with a ratchet gear 69, best shown in Figure 3, having 24 teeth, one for each hour of the day. The shaft 28, which as heretofore stated is turned through a quarter revolution each $\frac{1}{4}$ hour, is provided on the end opposite the quarter hour selector switches 55 with a metal 45 collar 70 having an eccentrically disposed pin 71 projecting from the face thereof and adapted to engage the teeth of the ratchet gear and impart step rotation to the shaft 62. The pin engages a tooth of the ratchet gear on the hour to advance the circuit closing arm from circuit closing position with one of the contacts 61 at the end of an hour period to circuit closing position with the next succeeding contact 61 and allow current to flow to the respective quarter hour selector switch of the hour just beginning. The pin 71 travels a circular path concentric with the shaft 28 as indicated by the arrowheads in Figure 3, and is out of engagement with the ratchet gear at all times except once during each hour to impart one step actuation to the hour selector switch shaft 62, or $\frac{1}{24}$ revolution, while the quarter hour selector switch shaft 38 is being moved through four step actuations, or one revolution.

Time synchronized dial

A clock dial 72 is provided with a hub 73 which is fixed to the hour selector switch shaft 62. The dial is provided with time designating numerals 74 which are visible through a sight opening 75 70 in the switchboard as best shown in Figure 1. The shaft 62 may be manually turned through the medium of the knob 64 to set the device to display the correct local time through the sight 75 openings.

Tuning relays

As shown in Figure 6, there are four tuning relays 53 in the present embodiment of the invention, corresponding to four broadcasting stations from which the operator desires to receive programs. However, as many tuning relays may be employed as desired and the contacts 12 on the dial switches 11 increased accordingly. One end of the coil of each relay is connected to a respective one of the wires 52 which leads to each contact 12 corresponding to a particular station such as for example WLW, on all of the dial switches 11. The other end of the coil is connected to a wire 76 which is connected to one end of the secondary winding of the transformer 22.

Each relay is provided with a spring pressed pivoted armature 77 which in normal position holds two switch contacts 78 in open circuit position. One of these contacts is mounted on a pivoted spring pressed arm 79 which is received in a hook 80 formed on the end of the armature 77. The arm 79 is connected by a wire 81 to a respective tuning condenser 82 which is connected by a wire 83 to one of the circuit wires 84 of the tuning circuit of the receiving set. The other contact 78 is connected by a wire 85 to the other circuit wire 86 of the tuning circuit.

Assume one of the dial switches 11 to be set by the operator to closed circuit position on a selected program contact 12. When the time arrives for that program to be heard the corresponding quarter hour selector switch will be actuated to closed circuit position, as previously described, and current will flow through the quarter hour selector switch, through the dial switch and through the tuning relay to energize the tuning relay and dislodge the hook 80. The circuit closing arm 79 immediately moves the contacts 78 to circuit closing position to energize the condenser 82 and tuning circuit 84-86 of the receiving set. Thus during a fifteen minute period the desired program will be tuned in and at the end of this period the time controlled switch 19 will be operated to close the motor circuit, the motor then turning the shaft 38 to energize relay resetting devices, presently described, and open the tuning circuit and power circuit of the receiving set to tune out the program.

The tuning relay 53 is not energized for the whole fifteen minutes a program is being received but is only energized momentarily to dislodge the hook 80 from the circuit closing arm 79 to permit the spring of this arm to hold the contacts 78 in circuit closing position for this specific time period. The circuit closing arm 46 of the quarter hour selector switch only has momentary wiping engagement with the contacts 43 and then passes off the contact to momentarily energize the tuning relay, thus economizing in current.

Power relays

There are four power relays 87, see Figure 6, connected in parallel with respective ones of the relays 53, and energized simultaneously with the energizing of the tuning relays 53. The power relays have a common spring pressed armature 88 adapted to be moved when any one of the power relays is energized. The armature terminates in a hook 89 which is normally lodged underneath a spring pressed pivoted circuit closing arm 91 which carries a switch contact 92 and which is connected to the 110 volt power circuit 75 of the set through the medium of a conductor

wire 93. A stationary switch contact 94 is connected by a wire 95 to the power circuit 23. When the armature 88 is attracted the hook 89 is disengaged from the circuit closing arm 91 and the controlling spring of this arm moves the contact 92 into engagement with the contact 94 and closes the power circuit to the set at the same time the tuning circuit is closed.

Resetting devices for the tuning and power relays

By referring to Figures 2 and 7 it will be seen that a relay resetting switch 96 is fixed to the shaft 28, comprising a disc of insulating material provided with four radially extending contacts 97 spaced 90 degrees apart. Current is conducted to these contacts through the medium of a brush 98 which has wiping engagement with the metal collar 10 and which is connected to the wire 68 from the transformer. The current passes from the collar through a metal bushing 99 into the contacts 97. A pair of brushes 100 and 101 have wiping engagement with the disc 96 and when the disc is turned in the direction of the arrowhead shown in Figure 6 one of the contacts 97 will first engage the brush 100 and subsequently will engage the brush 101.

The brush 100 is connected by a wire 102 to one end of an electro-magnet coil 103 shown in Figure 6. The other end of the coil is connected by a wire 104 to the aforementioned wire 76 which supplies current from the transformer to the tuning and power relays. The magnet 103 is provided with a pivoted angular armature 105 one end of which is engaged underneath the circuit closing arm 91 of the power relays. As previously mentioned when the motor turns the shaft 38 the power circuit will be opened to tune out a program and to accomplish this the brush 100 will be engaged by one of the contacts 97 on the resetting switch 96 and will close the circuit through the electro-magnet 103 whereupon the armature 105 will be attracted and will impinge against the circuit closing arm 91 and open the power circuit to the receiving set at the contacts 82 and 84. Immediately the controlling spring of the armature 88 of the power relays 87 will engage the hook 89 underneath the circuit closing arm 91 and hold the power circuit open.

The brush 101 is connected by a wire 106 to one end of an electro-magnet coil 107, shown in Figure 6. The other end of the coil is connected by a wire 108 to the aforementioned wire 76 which supplies current from the transformer to the tuning and power relays. The electro-magnet is provided with a normally gravitated armature 109 which is provided with a plurality of fingers 110 which underlie the circuit closing arms 79 of the tuning relays. As also previously mentioned when the motor turns the shaft 38 the tuning circuit will be opened to tune out a program and to accomplish this the brush 101 will be engaged by one of the contacts on the resetting switch 96 and will close the circuit through the tuning relay resetting magnet 107, whereupon the armature 109 will move the fingers 110 against the circuit closing arm 79 and open the tuning circuit at the contacts 78. Immediately the controlling springs of the armatures 77 of the tuning relays will engage the hooks 89 underneath the circuit closing arms 79 and hold the tuning circuits open.

Operation

The operator turns selected ones of the program selector switches to circuit closing position 75

at the selected station contacts, for example, he may wish to hear WGN at 1 o'clock, WLW at 1:15, WOR at 1:30, and no station from 1:45 to 2:00. He may then set the program selector switches accordingly, as indicated in Figure 1, for the hour beginning at 1 o'clock.

At 1 o'clock the striker 18 of the clock 6 will close the switch 19 to operate the motor controlling relay 24 and close the motor circuit at the contacts 25. The motor turns the gear 29 and shaft 28 together with all of the quarter hour selector switches through a quarter revolution at the end of which the motor circuit is opened at the motor relay switch 32, and also one of the quarter hour selector switches, corresponding to the program selector switch set at 1 o'clock, will have moved to circuit closing position closing the circuit of the tuning circuit relay corresponding to the WLW station and energizing the tuning circuit of the instrument to receive this station. Simultaneously the power relay corresponding to the station WLW will be energized to close the power circuit to the receiving set.

The station WLW will be heard from 1 o'clock to 1:15 and at the end of this fifteen minute period the motor will be again started to turn the shaft 28. When this occurs the reset electromagnets of both the tuning relay and the power relay will be operated by the reset switch 36 to open the tuning circuit and power circuit of the station WLW and reset both relays. This cycle of movement is repeated until the selected list of stations have been tuned in and out during the 24 hour period.

35 From the above description it is thought that the construction and operation of the invention will be fully understood without further explanation.

What is claimed is:

- 40 1. A radio program selector including a clock having a striking arm adapted to strike quarter hours, an electric motor, a shaft connected to the motor to be driven thereby, a source of electricity, a circuit for the motor connected to the source of electricity, a relay in said circuit, a switch in said circuit adapted to be closed by said striking arm to energize the relay and start the motor, a switch connected to said shaft and connected to the relay for de-energizing the relay to open the motor circuit and restrict rotation of the shaft to quarter turns, a switchboard, a plurality of manually operable dial switches on said switchboard each representing a respective quarter hour period, each dial switch having switch contacts representing respective broadcasting stations selectively receivable during the quarter hour period, tuning circuits, relays controlling the tuning circuits connected to respective ones of the dial switch contacts, rotary quarter hour switches connected to the shaft and each having contacts electrically connected to the contacts of a respective dial switch for completing one of said tuning circuits through a respective dial switch, a rotary hour selector switch connected to the source of electricity and having contacts each representing an hour period electrically connected to respective ones of the quarter hour switches, and ratchet means connected to said shaft for imparting step advance to the hour selector switch each hour.
- 45 2. A radio program selector including a quarter

hour time responsive switch adapted to be closed each quarter hour, an electric motor, a source of electricity, a circuit for the motor connected to the source of electricity and to the switch for starting the motor each quarter hour, a relay in said circuit, a shaft connected to the motor to be driven thereby, a switch connected to the shaft and to the relay for controlling the motor to rotate the shaft in quarter turns, a plurality of manually operable dial switches each representing a respective quarter hour period, each dial switch having switch contacts representing respective broadcasting stations selectively receivable during the quarter hour period, tuning circuits for a receiving set, relays controlling the tuning circuits connected to respective ones of the dial switch contacts, relays in the tuning circuits, rotary quarter hour switches connected to the shaft and each having contacts electrically connected to the contacts of a respective dial switch for completing one of said tuning circuits through a respective dial switch each quarter hour, a rotary hour selector switch connected to the source of electricity and having contacts each representing an hour period electrically connected to respective ones of the quarter hour switches, ratchet means connected to said shaft for imparting step advance to the hour selector switch each hour, a power circuit for a receiving set, and relays in the power circuit connected in parallel with the tuning circuit relays for supplying power to the receiving set simultaneously with energizing of any one of the tuning circuit relays.

3. A radio program selector including a quarter hour time responsive switch, an electric motor, a source of electricity, a circuit for the motor connected to the source of electricity and to the switch, the switch starting the motor each quarter hour, a shaft connected to the motor to be driven thereby, a switch connected to the shaft and connected in the motor circuit for controlling the motor to rotate the shaft in steps of a quarter turn each, a plurality of manually operable dial switches each representing a respective quarter hour period, each dial switch having switch contacts representing respective broadcasting stations selectively receivable during the quarter hour period, tuning circuits for a receiving set, relays controlling the tuning circuits connected to respective ones of the dial switch contacts, relays in the tuning circuits, relay resetting means for de-energizing the tuning circuits to turn off programs, a switch connected to the shaft and to the source of electricity, the last named switch being electrically connected to said relay reset means for actuating said means to turn off a selected program at the end of a quarter hour period, rotary quarter hour switches connected to the shaft and each having contacts electrically connected to the contacts of a respective dial switch for completing one of said tuning circuits through a respective dial switch each quarter hour, a rotary hour selector switch connected to the source of electricity and having contacts each representing an hour period electrically connected to respective ones of the quarter hour switches, and means connected to said shaft for imparting step advance to the hour selector switch each hour.
